UNITED STATES PATENT OFFICE.

HARRY E. KNOTT, OF WASHINGTON, IOWA, ASSIGNOR, BY MESNE ASSIGNMENTS, TO WASHINGTON MANUFACTURING COMPANY, OF WILMINGTON, DELAWARE, A CORPORATION OF DELAWARE.

MACHINE FOR MAKING PEARL-BUTTON BLANKS.

Application filed April 24, 1925. Serial No. 25,513.

My invention has to do with machines for cutting substantially rectangular button blanks from strips of shell.

It is my object to provide such a machine having parts so constructed and arranged that it may have a large capacity and be operated by one workman.

Another object is to provide in a machine of this kind endless carrying devices, each 10 provided with a plurality of blank strip holders.

Another purpose of my invention is to provide in such a machine means for automatically readjusting the remaining portion 15 of each strip to position for a further cutting operation after a blank has been cut therefrom.

Another purpose is to provide in a machine of this kind a large number of novel 20 combinations and mechanisms and features of structure hereinafter more fully described.

With these and other objects in view, my 25 invention consists in the construction, arrangement and combination of the various parts of my machine whereby the objects contemplated are attained, as hereinafter more fully set forth, pointed out in my claims, and illustrated in the accompanying 30 drawings, in which:

Figure 1 is a top or plan view of a machine embodying my invention, parts being broken away.

Figure 2 is a side elevation of the same, 35 parts being broken away.

Figure 3 is a rear elevation of the machine, parts being broken away and parts being shown in section.

Figure 4 is an elevation of part of the 40 operating mechanism viewed from the center of the machine taken on the line 4—4 of Figure 3.

Figure 5 is a top or plan view of a portion 45 of the machine, parts being broken away and parts being shown in section for illustrating the strip holding devices on the endless conveyors and some of the operating cams.

Figure 6 is a vertical, sectional view taken 50 on the line 6—6 of Figure 5.

Figure 7 is a similar view illustrating the parts in another position.

Figure 8 is a similar view illustrating the parts at a little later stage in the operation.

Figure 9 is a transverse, sectional view 55 taken on the line 9—9 of Figure 6.

Figure 10 is a perspective view of what I shall call the loading cam.

Figure 11 is a perspective view of the 60 discharging cam.

Figure 12 is a perspective view of another cam, which is the secondary discharging cam.

Figure 13 is a perspective view of a movable gate of the shell holding device; and 65

Figure 14 is a sectional view of a different form of the shell strip holder.

My present machine is one used in making pearl buttons. The process of manufacture involves cutting shells into strips by a 70 machine designed for that purpose. These strips are then cut into substantially rectangular blanks by the present machine. The blanks are then rounded and finished on other machines.

The process here mentioned involves a radical departure from previous commercial practice, and is referred to in certain prior patents, e. g., E. B. Hammer et al., No. 1,377,491, issued May 10, 1921 and H. H. 80 Knott et al. No. 1,315,673, issued September 9, 1919.

The designing of a machine for sawing or cutting pearl button blanks involves great difficulties on account of the brittleness of 85 the shells and the great variety of their shapes.

In providing a machine for sawing shell strips into rectangular blanks having sufficient speed and capacity to be commercially practical, it is necessary to provide mechanism for delicately handling the strips and for adjusting the strips for a series of cutting operations. This mechanism must be such as will handle strips of a great variety 95 of shapes and sizes.

In my present machine, I have provided a series of shell strip holders supported on a continuously moving conveyor or carriage. Suitable means are provided for successively subjecting the shell strip in each holder to a sawing operation, dropping out the sawed blank, adjusting the remaining strip for another sawing operation, and repeat- 100

ing the series of operations till the strip has been cut into substantially rectangular blanks.

In a general way, it may be said that my improved machine comprises a main frame on which is a plurality of laterally spaced endless conveyor chain structures, a pair of such conveyors being shown in this instance. Each chain structure carries a plurality of shell strip holders, each comprising a compartment, movable strip engaging fingers and a movable closure bottom or gate. The holders are loaded with shell strips at the front of the machine and as the upper stretches of the chain structures move rearwardly in the machine, rectangular blanks are cut from the strips. The gate and the holding fingers are operated by cams for discharging the blanks and releasing the strips to permit them to drop to position for cutting the next successive blank after each cutting operation.

The chain structures and associated parts are made substantially in duplicate simply for the purpose of increasing the capacity of the machine, and I do not desire in any way to limit myself to having one, two or any particular number of chain structures, although in the machines which have been built, two chain structures are employed.

The frame of my machine is indicated generally by the reference character 10 and is of proper size, weight and form to support the operative mechanisms. The frame may be supported upon legs 11. At the rear of the machine, a bracket frame 12, shown in Figure 3, is supported on the frame as on the rear legs 11. A transverse, driving shaft 13 is mounted in suitable bearings 14, which may be of the ball bearing type, on the bracket frame 12.

On the shaft 13 is a suitable gearing device, such as the belt pulley 15 from which rotation is transmitted to the shaft 13 for operating the mechanism of the machine.

Saws.

For each endless conveyor device, a series of saws is arranged in a row longitudinally of the machine.

Where the conveyor devices are in duplicate as here illustrated, there are two opposite rows of saws.

Mounted at the sides of the machine are upright brackets 16, which are supported in the following manner: Below one end of each bracket 16 is a lug 17 (see Figure 2) upon which the bracket is pivoted as by means of a bolt 18. This construction is illustrated also in Figures 1, where one of the brackets is shown in section at the lower left-hand part of the figure.

The bolt 18 is extended through a leg 19 of the bracket 16. At the other end of each

bracket 16 is a leg 20 having therein a slot 21 (see Figure 1) elongated on the arc of a circle, having its center at the center of the pivot bolt 18. Below each leg 20 is a lug 22 from which a pin 23 extends upwardly into the slot 21.

A set screw 24 mounted in the leg 20 projects into the slot 21 and limits the inward swinging movement of the bracket 16.

Each bracket 16 rotatably supports at its upper end a saw 25.

For operating the saws, there is mounted in each bracket a shaft 26 on which the saw is fixed. On each shaft 26 is a belt pulley 27. At the rear of the machine on the side thereof opposite the belt pulley 15, the bracket 12 is provided with an upward extension 28 on which are ball bearings or the like 29, in which an upright shaft 30 is journaled. (See Figure 3.)

On the shafts 13 and 30 are fixed intermeshing beveled gears 31 and 32, whereby rotation is transmitted from the shaft 13 to the shaft 30.

On the upper end of the shaft 30 is a belt pulley 33 in horizontal alignment with the belt pulleys 27. On the belt pulley 33 is a belt 34, which is threaded around the outer and forward faces of the rearward pulley 27 on the left-hand of the machine, thence across the machine around the opposite pulley 27, thence back across the machine around the next forward pulley 27 on the left side of the machine, thence across the machine around the opposite pulley on the right side, and so on until the belt has been threaded around all of the pulleys 27.

It is then extended around an idler pulley 35 suitably supported on the left-hand side of the machine, as shown in Figure 1, and thence around the belt tightener pulley 36 back to the pulley 33. The belt tightener pulley 36 is mounted on a swinging arm 37 and is held in contact with the belt 34 for tightening the same by means of a weight 38 supported on a rope or cable or the like 39.

The cable 39 is extended over a suitably supported pulley 40 (see Figures 1 and 3) and is secured to the arm 37, as shown in Figure 1.

Suitable casings 41 are provided for the pulleys 33, 35 and 36 as illustrated in Figure 1.

Casings 42 for the saws 25 are provided. The casings 42 have suitable slots in their walls as indicated at 43 in Figure 1, through which the saws project inwardly in the machine.

Connected with the casings 42 are dust take-off pipes 44. The dust take-off pipes 44 are connected by flexible tubes 45 (see Figure 2) with a manifold 46 from which the dust is drawn through the pipe 47 by

suction. One manifold 46 is provided for each row of saws.

It may be noted that the manifold is omitted from the lower part of Figure 1 and parts are shown in section on various lines for purposes of better illustration.

The manifolds 46 are supported on cross bars 48 resting on suitable brackets 49 extending upwardly from the main frame 10 as shown in Figures 2 and 3.

It may be briefly noted in this connection that the upper stretches of the endless conveyors move rearwardly in the machine and that the arrangement of the belt 34 is such that the various saws rotate as indicated by the arrow on the middle right-hand saw in Figure 1, so as to cut against the path of movement of the endless conveyors.

It may be mentioned at this time that the belts all tend to pull the saws inwardly in the machine. The inward movement is limited and controlled by the set screws 24 and the belt tightener pulley 36.

It is desirable to have some inward and outward adjustment of the shafts on which the saws are mounted, these being the shafts which carry the belt pulleys 27 in order to take into account the variation in the diameter of the saws, as they become worn and are re-filed.

This adjustment is had through the set screws 24, which permit adjustment of the brackets that carry the saws.

25 *Endless carriers and shell strip holders.*

At the front and rear of the machine are transverse shafts 50 and 51. The shaft 50 is mounted in bearings 52 shown in Figures 1 and 2. These bearings have elongated slots 53 through which are extended screw bolts 54 mounted in the frame of the machine.

By loosening the screw bolts, the bearings can be adjusted longitudinally of the machine. A set screw 55 is mounted in each bearing 52 with its head abutting against one of the lugs 17. The shaft 51 is mounted on the frame in suitable bearings 56.

50 For each endless conveyor, there are mounted on the shafts 50 and 51, large sprockets 57 and 58, each having a series of arms 59 with notches 60 in their outer ends. On each pair of sprockets 57 and 58, there is mounted an endless conveyor structure. These conveyor structures are connected with each other also in the manner herein-after described, so as to best operate in pairs.

60 There is arranged in the machine forming part of both of the endless conveyors, a series of spaced cross bars 61. Extending forwardly in the machine from each cross bar 61 is a pair of arms 62 and 63 (see Figure 1) and extending rearwardly is a similar

pair of arms 64 and 65. (See Figures 1 and 3.)

The arms 63 and 65 extending forwardly and rearwardly from the bar 61 may form a continuous rib across the top of the bar, 70 as illustrated for instance in Figure 1, whereas the arms 62 and 64 are so arranged as to permit space between them for the pivot for the shell engaging fingers herein-after referred to. 75

Each pair of forwardly extending arms 62 and 63 is pivoted by means of a pintle 66 to the rearwardly extending arms 64 and 65 of the next forward cross bar member 61. The cross bars and their connected arms thus form links and provide practically two spaced endless chains connected by the cross members 61. 80

It should be noted that the arms forming the links as hereinbefore explained have 85 roller carrying extensions 66^a projecting from said arms downwardly, for instance in the upper stretches of the endless conveyor device or upwardly in the lower stretches thereof, so that in the upper 90 rollers 67 project below the bars 61 to a substantial degree as clearly illustrated in Figures 2 and 3.

On each pintle 66 between the arms 62 and 63 is a roller 67 adapted at the proper points in the progress of the endless conveyor structures to coact with the notches 60. The length of such rollers is greater than the thickness of the sprockets 57 and 58 at the notches 60. 95

Suitably mounted on the frame at spaced points between the shafts 50 and 51 are brackets 68. Supported on the brackets 68 beneath the upper stretches of the endless conveyors are angle bars 69, the vertical flanges of which serve as tracks upon which the rollers 67 travel. 105

The horizontal flanges of the angle tracks 69 terminate at such points as illustrated at A (Figure 1) while the vertical flanges extend alongside the sprockets 57 and 58, as illustrated at B in Figure 1 in such manner that the rollers 67 may travel along said tracks and smoothly enter the notches 60. 115

The cross bars 61 have lugs 70 projecting therefrom. Supported on pins 71 on the lugs 70 are rollers 72 (see Figures 1 and 3).

It will be noted that the rollers 72 are arranged near the middle of the machine. 120

In the upper part of the machine, longitudinally arranged, parallel bars 73 are spaced from each other in such manner that the rollers 72 travel between them for thus taking the lateral thrust of the endless conveyor devices. 125

On each bar 61 is mounted a roller 74 which projects upwardly from the upper bars 61 and downwardly from the lower 130

bars 61 about midway of the length of said bars.

A centrally arranged bar 75 is mounted on the machine extending longitudinally thereof and is so located that the rollers 74 of the lower stretch of the endless conveyor structures travel on the bar 75 as illustrated in Figure 2 for preventing sagging of the parts.

It will thus be seen that I have provided what may be called a pair of endless conveyor chains connected by the cross bars 61. The cross bars 61 each have at their free ends the forwardly extending arms 62 and 63 and the rearwardly extending arms 64 and 65. The arms of each cross bar 61 are pivotally connected with the arms of the next cross bar 61 on both sides of the particular bar under consideration.

Shell strip holders.

Supported on the endless conveyor structures are shell strip holders. Mounted on the outer side of each arm 65 is a shell strip holder member, which for convenience I will call the receiver. This is a box-like structure, which will be seen by reference to Figures 3, 5, 6, 7, 8 and 9, and consists of an inner wall 76 having at one end a downward extension 77 (see Figure 8) an outer wall 78, a cross wall 79 at the follower end of the receiver, and a curved bottom member 80 terminating substantially short of the cross wall 79.

There is thus left an open passage 81 at one end of the bottom member 80 adjacent to the cross wall 79.

Considering the parts in their position while in the upper stretch of the conveyor, it will be noted that the cross wall 79 below the level of the bottom member 80 is inclined away from the bottom member 80 as at 79^a. The face of the extension 77 is provided with a groove, as at 82, designed to receive the saw blade, so as to permit a shell strip in the receiver to be sawed entirely through without permitting the saw teeth to strike the extension 77.

The outer wall terminates at its lower edge flush with the edge of the groove 82. (See Figure 2.) The wall 76 is secured to the arm 65 by means of screw bolts 83. The wall 78 is provided with holes 84 opposite the screw bolts 83 to permit the insertion of a screw driver for working on the screw bolts 83.

Below the outer side 78, a side plate 85 is secured to the lower part of the cross wall 79 below the groove 82 by means of a screw bolt 86.

It may be said in this connection that the cross wall 79 has a groove or slot 82^a (Figure 8) extending across it for the reception of the saw.

Within the receiver adjacent to the lower part of the cross wall 79 is a rubber block

or the like 88 fastened in place by means of a screw bolt 90 extending through the plate 85, the block 88 and into the extension 77.

Mounted on the upper portion of the cross wall 79 is a spring device 91 which normally projects slightly away from the wall 79 into the receiver, as illustrated in Figure 8. The purpose of this spring device will be hereinafter again referred to.

The mussel shells from which buttons are made are cut into strips by another machine and the strips are fed into the receiver now being described in any suitable way with one end projecting downwardly through the opening 81.

For holding the strips in the receiver, I provide a movable bottom member or gate arranged substantially below the opening 81, and I provide upper and lower engaging fingers adapted to engage the shell strip above and below the saws. In the accompanying drawings, I have indicated the shell strip by the reference numeral 92.

To prevent the shell strip 92 from dropping out of the receiver when it is fed thereto in the upper stretch of the endless conveyor, I provide a movable bottom or gate member 93 for the receiver. This gate member 93 is shown in perspective in Figure 13 on the first sheet of the drawings. It is pivoted on a pin or bolt or the like 94 supported on the cross bar 61 between the receivers and the rollers 74.

This movable gate 93 is shown in Figures 6 and 8 in its closed position and in Figure 7 in its open position.

In its closed position, it will, of course, be understood that the gate 93 forms a closure member for the bottom of the receiver below the opening 81.

Means for swinging the gate 93 on its pivot will be described hereafter.

Above the gate 93 so arranged as to travel below the saws 25 is mounted on each pin 94 a lower shell engaging finger 95 having in one end an extension 95^a shown in Figures 5 and 6, which extension is adapted in one position of the pivotal movement of the finger 95 to project below the opening 81 for holding the lower part of a shell strip 115 against the rubber block 88 as illustrated in Figure 6.

The extension 95^a has preferably a rubber tip 96 for engaging the shell. The method for operating this finger device will be hereinafter explained.

An upper finger 97 is pivoted on the same pin 94 already referred to at such a point that (referring to the parts in the upper stretch of the endless conveyor structure) the engaging finger 97 is above the saw.

The finger 97 has at one end an extension 98 adapted to project into the receiver below the opening 81 so as to engage the shell strip 92, as illustrated in Figures 6 and 7.

I will now refer to the means for operating the gate member 93 and the shell engaging fingers 95 and 97.

It may be mentioned that these fingers and the gate member are always normally held in closed position by means of springs 99, 100, and 101. (See Figures 2 and 5.)

For opening the engaging fingers and gate at the proper times in the travel of the endless conveyor devices, I provide a series of cams.

Extending lengthwise of the machine below the bars 61 and supported on the brackets 68 is a longitudinally arranged bar 102. (Figs. 1, 3 and 5.)

The engaging fingers and the gate member 93 have portions extending toward the center of the machine a sufficient distance so that the operating cams for the upper stretch 20 of the endless conveyor structure for properly actuating said engaging fingers and gates during the sawing operations, may be located on said bar 102.

What I may call the opening cam is shown in Figure 10. It comprises a bracket device 103 having a sleeve 104 mounted on the shaft 50. The bracket 103 is fixed to one end of the bar 102. Supported on the bracket 103 and on the bar 102 is a double cam 105. This cam is double for operating the engaging fingers on both sides of the machine.

When the receivers travel upwardly over the sprockets 57 at the forward end of the machine, the inwardly extending arms of the engaging fingers 95 and 97 strike the forward ends of the double cam 105, thus swinging the engaging fingers on the pivot pins 94 for causing the extensions 95^a and 98 to be held in their open positions as illustrated in Figure 8, during a substantial distance of the travel of the receiver.

While the engaging fingers are thus both in open position, such being the position illustrated in Figure 8, one shell strip 92 is dropped into each receiver where it occupies the general position shown in Figure 8.

Shortly thereafter the engaging fingers reach the inclined portions 106 of the double cam 105 and the springs 100 and 101 move the engaging fingers 95 and 97 on the pivot pin 94 until the sections 95^a and 98 engage the shell strip, as illustrated in Figure 6, firmly gripping its lower portion against the rubber block 88 and its upper portion against the spring 91, and pressing said spring against the cross wall 79.

As the receivers advance, they reach the first saws, and a shell blank 107 is cut from the strip 92 by the saw 25, as illustrated in Figures 5, 6 and 9.

Certain of the details of the sawing operation and of the structure of the gate 93 will be hereafter referred to.

There is provided on the bar 102 a series of triple cams C, one of which is shown in perspective in Figure 11, arranged for operating the engaging fingers and gate after each sawing operation.

In Figure 6, the parts are illustrated in their position during the sawing operation.

Immediately after the completion of each sawing operation and as the strip holders move rearwardly in the machine, the inwardly projecting portion of the gate engages the shoulder 108 of the cam member 109 of the triple cam C. (See Figure 5.)

At the same time, the inwardly projecting portion of the lower engaging arm 95 engages the shoulder 110 of the cam member 111 of the triple cam C. The gate 93 and engaging finger 95 are then moved to their positions illustrated in Figure 7, which permits the shell blank 107 to be dropped downwardly into the chute 112, the lower parts of which are laterally inclined and may discharge into any suitable receptacle provided for the blanks. The chutes 112 are supported at their upper ends on the angle tracks 69, by rivets or bolts 112^a and at their lower ends on the frame 10 by screws 112^b as shown in Figure 3.

The cams C and the chutes 112 are so arranged as not to interfere with the belt 34. This fact explains why in Figure 5, the cams C and chutes 112 are slightly staggered at some places in the machine.

As the shell strip holders move rearwardly in the machine, the gate quickly passes the portion 113 of the cam 109 (see Figure 11) and begins to slide down the inclined face 114 of said cam for permitting the gate to close.

The finger 95 travels along the face 115 of the cam member 111 for some distance after the gate has closed. This is for the purpose of permitting the remaining portion of the shell strip to drop down from the position shown in Figure 7 to the position shown in Figure 8.

Before the finger 95 leaves the face 115 of the cam 111, the inwardly projecting portion of the finger 97 engages the shoulder 116 of the cam member 117 of the triple cam C for moving the finger 97 to inoperative position where it releases the shell strip. Thereupon the shell strip drops from the position shown in Figure 7 to the position shown in Figure 8. This dropping may be assisted by mechanism which will be hereinafter more fully referred to in the fuller description of the operation of the machine.

When the finger 95 clears the face 115 and begins traveling down the inclined face 118, the finger 95 moves to position for engaging the lower part of the shell blank below the saw level, the position being illustrated in Figure 6.

It will be seen that the finger 97 travels along the face 119 of the cam member 117 for a slight distance, after the finger 95 begins to move to operative position, and 5 then travels down the inclined face 120 for permitting the finger 97 to move to its position shown in Figure 6 for holding the shell strip.

The shell strip is then held in position 10 for another sawing operation, which occurs when the holder moves to position for co-operation with the next succeeding saw.

As many saws may be provided as is desired. I preferably employ five saws on a 15 side, because ordinarily five saws will cut the shell strip into six parts and this is as many as the ordinary strip will supply.

It sometimes occurs that there is a small piece of shell strip left when the holders 20 travel around the sprockets 58, and I have therefore mounted on the bracket structure 68 at the lower part thereof a double cam 121, shown in Figures 3 and 12, having the two inclined or cam faces 122.

25 This cam 121 is so arranged that as the inverted holders travel forwardly in the machine, after they have traveled around the sprockets 58, the inwardly projecting portions of the fingers 95 and 97 engage the shoulders 123 for causing the fingers to be moved to inoperative position for releasing and dropping any shell parts that may remain in the holders. The lower strip of the endless conveyor is omitted from Figure 3 to better illustrate the parts.

35 The parts are preferably so arranged that all the saws operate simultaneously.

Shell holder advancing means.

40 The shell holders are advanced by rotation of the shaft 51 and the sprockets 57 and 58. The mechanism for rotating the shaft 51 will now be described.

On the shaft 13 is a fixed pulley 124 and 45 adjacent thereto a loose pulley 125. Suitably mounted on a bracket 126 (Figure 2) is a stub shaft 127 on which is a pulley 128. A belt 129 travels on the pulley 128 and on either of the pulleys 124 or 125.

50 I provide a belt shifter for moving the belt 129 from the pulley 124 to the pulley 125 or back. This belt shifter comprises a transverse rod 130 shown in Figure 3, having the downwardly projecting fingers 131 55 receiving between them the belt 129.

At the side of the machine, the rod 130, as shown in Figure 2, is pivoted to a lever rod 132 which extends toward the forward end of the machine at the side thereof. The 60 rod 132 is pivoted on the bracket 133, as at 134 (Figures 1 and 2) and projects forwardly to position where it is readily accessible to the operator.

A support 135 may be provided for the

rod 132. By shifting the belt, the strip holders may be thrown into and out of gear.

On the shaft 127 is a beveled gear 136 shown in Figure 2, which meshes with a beveled gear 137 on an upright shaft 139 suitably journaled on the bracket 126.

70 On the shaft 139 is a worm 140, which meshes with a worm wheel 141 loosely mounted on a stub shaft 142 extending from a boss on one of the legs 11 of the machine.

75 The mechanism for transmitting motion from the shaft 142 to the shaft 51 is shown as viewed from the side of the machine in Figure 2, and as viewed from the inside of the machine in Figure 4.

80 Pivoted on the stub shaft 142 is an upwardly projecting arm 143.

Secured in the arm 143 are stub shafts 144 and 145. Loosely mounted on the shaft 142 and secured to the worm wheel 141 is 85 a spur gear 146 meshing with a spur gear 147 on the shaft 144. The spur gear 147 meshes with a spur gear 148 on the shaft 145. On the shaft 51 is a large pinion 149. A short shaft 150 is mounted on a stud 151 on 90 the frame. (Figs. 3, 4.)

95 Loosely mounted on the shaft 150 is a spur gear 152 arranged in mesh with the pinion 149. Fixed to the spur gear 152 but arranged off-center on the shaft 150 is a spur gear 153, which meshes with the spur gear 148.

For holding the spur gears 153 and 148 in mesh, the following means is provided.

100 On the shaft 145 is mounted a disc 154, the circumference of which is on the pitch line of the gear 148. Fixed to the gear 153 and rotatably mounted off-center on the shaft 150 is a disc 155 (see Figure 2), the circumference of which is on the pitch line 105 of the gear 153.

110 The discs 154 and 155 are rotatably received in a plate 156 for the purpose of holding the edges of the discs in contact and holding the gears 153 and 148 in mesh.

115 It will be seen that rotation of the worm gear 141 rotates the gear 146, the gear 147, the gear 148 and the gear 153, which imparts rotation to the gear 152 which is secured to the gear 153 and thereby rotates the gear 149.

120 On account of the eccentric mounting of the gear 153, the rotation imparted to the gear 149 is irregular in speed due to the varying radius of the teeth on the gear 153. The parts are so arranged that the gear 149 is slowed down for slowing down the movement of the sprockets 58 and the shell strip holders during the sawing operation, and is speeded up for speeding up the travel of the shell strip holders between the sawing operation.

125 In Figure 14, I have shown a slightly dif-

ferent form of the shell strip holder in which the spring clip 91 and the rubber block 88 are omitted.

Operation.

I will now describe in greater detail, the operation of my improved shell blank making machine and during such description will explain in greater detail certain features of the structure of the machine.

Suitably mounted at the front of the machine above it is a hopper 157 from which a chute 158 extends downwardly and forwardly to a transversely arranged box or the like 159 supported on brackets 160 at the front of the machine.

The operator takes the shell strips from the box 159 and inserts them large end down into the holders in approximately the position illustrated for instance in Figure 8.

This is done during the time the loading cam structure, illustrated in Figure 10, is holding the engaging fingers 95 and 97 in inoperative position as the shell holders travel upwardly over the upper forward part of the sprockets 57.

Just after the shell strip holders leave the position above the shaft 50, the holding fingers 95 and 97 reach the inclined faces 106 of the double cam 105, and the springs 100 and 101 move the engaging fingers to their positions shown in Figure 6 for holding the shell strip in the holder. (See Figures 2, 10 and 6.)

It will be noted that what may be called the closing of the finger 97 presses the spring device 91 against the forward face of the wall 79, as shown in Figure 6.

All of the shell holders are loaded as they travel upwardly around the sprockets 57.

As the shell holders move rearwardly in the machine, the first sawing operation occurs.

It will be remembered that the wall 78 of the shell holder (see Figure 9) stands above the saw level and the plate or wall member 85 stands below the saw level, thus leaving a slot through which the saw may project into the shell holders.

The extension 77 has a groove 82^a, which during the sawing operation is on a level with the saws to permit the saws to saw entirely through the shell strip without contact with the extension 77 of the wall 76.

Sometimes the shell strip breaks for a short distance as indicated at 161 in Figure 9.

This is caused by the adjustment of the saw not allowing it to extend into the groove 82^a. In this event the spring tension of the fingers 95 and 97 pressing against the shell strip 91 (which has its outwardly curved side against the back wall of the shell strip holder pocket) is sufficient to cause the break at 161.

When the shell strip does so break instead of being sawed entirely through, there is likely to be left a sharp point at the point of breakage 161, so that when the upper portion of the shell strip is dropped downwardly from its position shown in Figure 7 to the position shown for instance in Figure 8, the point thus mentioned would rest upon the gate 93.

The result of this, if unprovided for, would be that the shell blank 107 next to be cut would not be of the proper width from top to bottom.

In order to provide for such contingencies, the gate 93 is provided with a notch 162, shown in Figure 13, and also in Figure 9, where the short extension caused by the breaking of the strip is indicated by the reference character 163.

This extension 163 drops into the slot 162 so that the smoothly sawed under surface of the blank 107 may rest upon the gate 93.

When the holder advances after the sawing operation is completed, the cam 3 is reached and the gate and the lower engaging finger 95 are opened and released.

They then stand in the position shown in Figure 7 and the shell blank 107, which has been cut off drops into the chute 112. The finger 97 is then moved to inoperative position, as shown in Figure 8.

For insuring the positive movement of the remaining portion of the shell strip downwardly in the holder, I have provided the following means:

Supported on the cross members 48 are longitudinally arranged strips 164, shown in Figures 1 and 8. Pivoted to the strips 164 and hanging downwardly therefrom are short strips 165 having in their lower forward faces notches 166. These strips 165 are so arranged that they stand in the path of the shell strips 92 for engaging the upper portions of said shell strips, as shown in Figure 8, just after the engaging fingers 97 open or move to inoperative position.

It should have been mentioned perhaps that before the shell strips reach the strips 165, and immediately following the opening of the engaging fingers 97, the springs 91 kick the shell strips rearwardly slightly to insure that the lower ends of the shell strips will clear the rubber blocks 88 and drop downwardly upon the gates 93. (See Figure 8.)

The notches 166 are beveled and the strips 165 are of light weight so that immediately after the closing of the fingers 95 and 97, the strips 165 slide freely over the shell strips and the walls 79.

The sawing operation is repeated until all the saws have operated or the shell strips of the length being used have been sawed up.

If the operation is slowed down during the sawing operation, it is speeded up be-

between sawing operations in the manner hereinbefore referred to.

If there are any pieces of shell strips left in the holders, after they pass over the sprockets 58, such pieces are dropped out by virtue of the operation of the cam 121.

As the saws are filed and become smaller in diameter, they may be adjusted inwardly by means of the set screws 24 hereinbefore referred to.

It will be seen that this machine provides a means whereby the operator may load the shell holders with speed and that thereafter the operation of the machine is automatic.

This machine is one of a series of machines.

It will be understood that a different machine is used for cutting the shells into strips, then the strips are cut into blanks by the present machine and another machine rounds the blanks.

It should perhaps be mentioned that heretofore the process generally used for cutting button blanks has been that in which round blanks were cut from the shells by means of tubular saws. I have demonstrated that by the method employed in the series of machines just mentioned a very substantial larger number of blanks is secured from the shells and the total process may be so speeded up that buttons may be made with a very substantial saving of labor and time.

It will be noted that the side thrust is minimized by the arrangement of the saws in opposite pairs and also by the use of the bars 61, the rollers 72 and the bars 73.

Another advantage of the structure here disclosed arises from the fact that the blanks cut from the thicker portions of the shells, by the forward saws are discharged into chutes by themselves, whereby the thicker blanks are sorted and separated from the thinner ones.

I have shown in Figure 14, the shell holders, without the clips 91, the rubber blocks 88 or the devices 165. I believe they may be dispensed with in actual practice, and in a machine which I have built, have found the operation successful without them.

It will of course be understood that changes may be made in the construction and arrangement of the parts of my improved machine without departing from the real spirit and purpose of my invention, and it is my intention to cover by my claims, any modified forms of structure or use of mechanical equivalents, which may be reasonably included within their scope.

I claim as my invention:

1. In a machine of the class described, a frame, a series of saws supported thereon, an endless conveyor structure having shell holders, each provided with side walls and one end wall, a spring adjacent said end wall and secured thereto, a movable gate and

a pair of movable gripping fingers, said fingers serving to hold the shell against the end wall and the spring, means for releasing said fingers whereby the shell is released and said spring operates to move said shell and free it so that gravity will thereafter move the shell downwardly.

2. In a machine of the class described, a frame, a plurality of saws thereon, an endless conveyor device having a series of shell holder receptacles, each of said shell holder receptacles having side walls and one end wall, a movable gate and a pair of movable fingers for cooperating with each holder for holding a shell in position to be sawed, said fingers being arranged to be above and below the saws during the sawing operation, means for opening the gate and moving the lower finger to inoperative position after each sawing operation, said means being adapted to release the gate and permit it to close before the lower finger is permitted to move back to operative position, means for then moving the upper finger to inoperative position, and a kicker spring on said holder for then actuating the shell remaining in the holder.

3. In a machine of the class described, a frame, a plurality of saws thereon, an endless conveyor device having a series of shell holder receptacles, each of said shell holder receptacles having side walls and one end wall, a movable gate and a pair of movable fingers for cooperating with each holder for holding a shell in position to be sawed, said fingers being arranged to be above and below the saws during the sawing operation, means for opening the gate and moving the lower finger to inoperative position after each sawing operation, said means being adapted to release the gate and permit it to close before the lower finger is permitted to move back to operative position, means for then moving the upper finger to inoperative position, and a kicker spring on said holder for then actuating the shell remaining in the holder.

3. In a machine of the class described, a frame, a plurality of saws thereon, an endless conveyor device having a series of shell holder receptacles, each of said shell holder receptacles having side walls and one end wall, a movable gate and a pair of movable fingers for cooperating with each holder for holding a shell in position to be sawed, said fingers being arranged to be above and below the saws during the sawing operation, means for opening the gate and moving the lower finger to inoperative position after each sawing operation, said means being adapted to release the gate and permit it to close before the lower finger is permitted to move back to operative position, means for then moving the upper finger to inoperative position, and a kicker spring on said holder for then actuating the shell remaining in the holder, and a hook for engaging the free end of the shell for then moving it toward sawing position.

4. In a machine of the class described, a frame, a plurality of saws mounted thereon for rotation, an endless carrier device having thereon a series of shell strip holders or pockets each having side walls and an end wall at one end thereof and a bottom terminating short of the end wall, a movable gate adapted to normally stand below the side walls for supporting a shell strip, a pair of movable fingers adapted during the sawing operation to be above and below the saw for holding a shell strip in sawing position resting on said gate, and means for actuating said gate and fingers for holding them in operating position during the sawing operation and for then releasing the sawed blank, closing the gate, and releasing the remaining

115

130

shell element, a hook pivoted on said frame in position to engage one end of the shell strip after it is released and thereby move the strip endwise as the endless carrier device moves the pocket, said finger actuating means subsequently moving the fingers to operative position.

5. In a machine of the class described, a frame, a plurality of saws mounted thereon for rotation, an endless carrier device having thereon a series of blank holders or pockets, each having side walls and an end wall at one end thereof, and a bottom terminating short of the end wall, a movable gate adapted to normally stand below the open space between the bottom and the end wall, and a pair of movable fingers adapted during the sawing operation to be above and below the saw for holding a shell strip in sawing position resting on said gate, and means for actuating said gate and fingers for holding them in operating position during the sawing operation and for then releasing the sawed blank, closing the gate, releasing the remaining shell element and subsequently moving the fingers to operative position, and means for positively moving the shell toward sawing position while the fingers are inoperative, said endless carrier device traveling in substantially a horizontal plane, and means for rendering the fingers of the lower stretch of the carrier device inoperative at one period in the movement of the device.

6. In a structure of the class described, a

holder for curved shell strips comprising a wall, a pair of fingers for holding the outwardly curved side of the shell strip against said wall, a saw for cutting the strip between the fingers, said fingers serving to break the strip adjacent the saw cut when the cut is nearly completed.

7. In a structure of the class described, an endless carrier, shell strip pockets carried thereby, fingers extending into each pocket for holding the strip therein, a gate against which the shell strip rests, saws for cutting the shell strip into blanks, means for releasing the fingers and the gate for releasing the blank and moving the strip to a new position, said endless carrier inverting the pockets and means for moving the fingers while the pockets are inverted and thereby releasing any shell strip held by them.

8. In a structure of the class described, a holder for curved shell strips comprising a wall, a pair of fingers for holding the outwardly curved side of the shell strip against said wall, a saw for cutting the strip between the fingers, said fingers serving to break the strip adjacent the saw cut when the cut is nearly completed, a gate below the bottom of the pocket for supporting the shell strip, a notch in said gate for allowing the broken corner of the strip to extend below the surface of the gate.

Des Moines, Iowa, March 2, 1925.

HARRY H. KNOTT.
